(57) CLAIM

We claim the ornamental design for a robotic lawnmower, as shown and described.

DESCRIPTION

FIG. 1 is a front right perspective view of the present invention;

FIG. 2 is a rear left view of the present invention;

FIG. 3 is a rear perspective view of the present invention;

FIG. 4 is a top plan view of the present invention; and,

FIG. 5 is a bottom plan view of the present invention.

The broken line illustrations in the drawing disclosure do not constitute part of the design sought to be patented.

1 Claim, 5 Drawing Sheets
